UNITED STATES PATENT OFFICE.

DANIEL E. HENNESSY, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

APPARATUS FOR MAKING BEADS.

Application filed October 27, 1924. Serial No. 746,255.

My invention relates to a device for forming bead cores and more particularly for forming that type of core which contains a plurality of metal cables or grommets.

5 Among the objects of my invention is to provide a device by means of which the cables or grommets and the filler material of the bead core may be assembled in a single operation ready to be inserted as a unit into 10 the mold. Other objects will be apparent from the following specification and claims.

In the drawings accompanying this specification and which discloses one embodiment of my invention,

15 Figure 1 is a front elevation of the device, Figure 2 is a plan view of the structure shown in Figure 1,

Figures 3 and 4 are diagrammatic views showing the manner of operation,

20 Figure 5 is a section substantially on line 5—5 of Figure 4,

Figure 6 is a section substantially on line 6—6 of Figure 4,

25 Figure 7 is a section substantially on line 7—7 of Figure 4,

Figure 8 shows a molded bead in sections, and

Figures 9, 10, and 11 are figures corresponding to Figures 5, 6, and 7 but showing 30 a modified form of bead core.

Referring to the drawings 1 indicates a standard provided at the top with a table 2.

A main drive shaft 4 is rotatably mounted in bearings 6 and 7, supported respectively

35 by brackets 8 and 9 secured to table 2. Power is transmitted to the shaft 4 through a loose pulley 10 adapted to be operatively connected to the shaft 4 by clutch 12 operated from pedal 14 through rod 15 and bell-

40 crank 16 in an obvious manner. Hand wheels 18 and 19 are provided on the ends of shaft 4 for the purpose of hand operation in starting the grommets and filler strip as later described. Shaft 4 is provided near

45 its right hand end, as seen in Figures 1 and 2, with a worm 20 meshing with worm gear 21, mounted on transverse shaft 22 supported in bearings 23 and 24 formed in brackets 25 and 26 secured to bracket 9.

50 Supported on the forward end of shaft 22 is a drum 28 provided with spaced grooves 29. Drum 28 is mounted slightly eccentrically on shaft 22 for reasons later explained.

Positioned in alignment with drum 28 is a 55 second drum 30 provided with grooves 31

similar to grooves 29, the outer flanges of drum 30, however, being substantially deeper than those of drum 28. Drum 30 is freely mounted on a shaft 27 secured to a carriage 32 provided with bearings 33 slidable on guides 34 supported by a bracket 35 secured to standard 1. Secured at one end of guides 34 is a compressed air cylinder 36 in which a piston 38 secured to carriage 32 operates. Compressed air is admitted and exhausted from cylinder 36 through pipe 40 controlled by valves 41 adapted to alternatively connect pipe 40 to a source of compressed air thru pipe 42, or vent it to the atmosphere. The valve is controlled by foot-throttle 44.

60 These air connections may be of any conventional type and detailed description of them is believed unnecessary. As will be evident from an inspection of Figure 2 the compressed air entering cylinder 36 will move carriage 32 to the left. Upon exhaustion of the air in cylinder 36, carriage 32 is moved to the right under the influence of weight 46 connected to carriage 32 at 47 by cable 48.

65 A flanged roll 50 is rotatably mounted in a bracket 51 secured to carriage 32 at 52. Roll 50 as shown in Figure 1 is positioned adjacent drum 30 and the flange 54 of said roll is in alignment with the central flanges of drums 30 and 28. Mounted in an arm 56, 70

adjustably secured at 57 to a member 58 adjustably secured in turn at 59 to bracket 35, is a grooved roll 60 hereinafter referred to as the folding roll. Roll 60 is positioned to fit nicely between the outer flanges of roll 30 75 when the latter is in its outward position as shown in Figure 4. A spring 61 urges arm 56 downwardly against an adjustable stop 63. A shaft 66 adapted to support a roll of fabric is rotatably mounted on bracket 68 80 secured to table 2. Shaft 66 is positioned as shown in Figures 1 and 2 in substantial alignment with drums 28 and 30.

85 Brackets 26 and 35 are preferably extended to form holders 37 and 45 for grommets 100 and finished cores respectively.

The operation is as follows:

With drum 30 in the position shown in Figure 3 grommets 70 are positioned in grooves 29 and 31 as shown in Figure 3. 105 Air is then admitted to cylinder 36, to move drum 30 to the position shown in Figure 4 thus putting the grommets under tension. Power is now applied through pedal 14 to drive drum 28 thus driving the grommets 110

forward and rotating drum 30. Due to the eccentric mounting of drum 28 an increased tension is intermittently applied to the grommets thus removing any kinks in the 5 grommet wires and seating them properly in the grooves of the drums. The clutch is then released. As shown in Figure 1 the grommets as they pass over roll 50 are positioned on either side of flange 54. A strip 10 of fabric 71 preferably heavily coated with rubber is drawn from a supply roll supported on shaft 66 and fed beneath the grommets as they rest on roll 50 as shown in Figure 5. As shown in the latter figure, 15 flange 54 serves to fold the fabric strip upwardly between the grommets. Strip 71 is further fed forwardly until engaged between the grommets and drum 30 as shown in Figure 6. During these operations drum 20 28, and thereby the grommets 70, are preferably rotated through hand wheels 18 or 19. Pedal 14 is now depressed to again apply power to shaft 4, to rotate drum 28, grommets 70 and drum 30 strip 71 is thus 25 drawn forward beneath and between the grommets and around drum 30 as shown in Figure 6. Folding roll 60 as previously stated engages between the flanges of drum 30 and as the strip 71 passes beneath the 30 folding roll the edges of the fabric strip are thereby folded down into contact with the upwardly folded intermediate portion of the strip, as clearly shown in Figure 6. This operation is continued until the grom- 35 mets are completely wrapped, the fabric strips being severed and the end overlapped to complete the wrapping.

It is obvious that the wrapping could be continued to apply a plurality of layers of 0 fabric to the grommet but I prefer to use a single wrapping with a fabric sufficiently heavy to supply all the necessary filler.

Air is now exhausted from the cylinder 36, carriage 32 moving to the right under 45 the influence of weight 46, permitting removal of the completely formed bead core. The bead is now ready to be placed as a unit in a vulcanizing press to be semi-cured, the so cured bead core being shown in Figure 8.

It will be obvious that by forming a suitable number of grooves in drums 28 and 30 and providing additional flanges on roll 50

that bead cores may be formed with any desired number of grommets. Figures 9, 55 10, and 11 corresponding to Figures 5, 6, and 7 show the formation of a three-cabled bead core.

It will be understood that the specific embodiment of my invention above described 60 is illustrative only and my invention is not limited thereto,

I claim:

1. A device of the character described comprising a roll provided with spaced 65 grooves adapted to receive grommets, the center ridge defining said grooves adapted to raise the central portion of a strip of wrapping material between the grommets and a second grooved roll the flanges of 70 which are adapted to engage the interior faces of the outer flanges of the first mentioned roll in position to engage and fold the edges of a strip of material about the grommets positioned in the grooves. 75

2. A device of the character described comprising aligned grooved rolls provided with spaced grooves adapted to receive endless grommets and a strip of material, means for reciprocating one of said rolls, a flanged 80 roll adapted to force the central portion of the strip of material between the grommets, a folding roll adapted to fold the edges of the material about the adjacent grommets and means to rotate one of said first men- 85 tioned rolls.

3. A device of the character described comprising aligned rolls provided with spaced grooves adapted to receive endless 90 grommets, means for reciprocating one of said rolls to permit positioning of the grommets and apply tension thereto, means to rotate one of said rolls, a flanged roll so positioned that its flange projects between the grommets, and adapted to force the center portion of a wrapper strip between the grommets, and a grooved folding roll the flanges of which engage the interior faces of the outer flanges of one of the first mentioned rolls to fold the edges of the wrapper 100 strip about the grommets and into overlapping relation. 95

In testimony whereof I have signed my name to the above specification.

DANIEL E. HENNESSY.
